UNITED STATES PATENT OFFICE.

FRANZ MARKGRAF, OF NEW YORK, N. Y.

VARIABLE-SPEED AND REVERSING GEAR.

No. 872,952.

Specification of Letters Patent.

Patented Dec. 3, 1907.

Original application filed February 11, 1903, Serial No. 142,974. Divided and this application filed December 15, 1904.
Serial No. 236,950.

To all whom it may concern:

Be it known that I, FRANZ MARKGRAF, residing at New York, in the county of New York and State of New York, have invented 5 certain new and useful Improvements in Variable-Speed and Reversing Gears, of which the following is a full, clear, and exact description, such as will enable others skilled in the art to which it appertains to make and 10 use the same.

This invention relates to variable speed mechanism.

The invention comprises certain features divided from my co-pending case, Serial No. 15 142,974, filed February 11, 1903, in accordance with the Office requirement.

One of the objects thereof is to provide a compact and efficient mechanism of the above type whereby the speed of a driven member 20 may be changed without substantial shock or injury to the parts.

Another object is to provide a device of the above type having no delicate parts to jam or otherwise become inoperative.

25 Another object is to provide mechanism of the above type in which the speed of a driven part may be varied and the direction of rotation thereof changed by the manipulation of a single lever.

30 Other objects will be in part obvious and in part pointed out hereinafter.

The invention accordingly consists in the features of construction, combinations of elements and arrangement of parts exemplified in the mechanism herein described and the scope of the application of which will be indicated in the claims at the end of this description.

In the accompanying drawings, in which 40 are illustrated two of various possible embodiments of my invention, Figure 1 is a side elevation of one of the same. Fig. 2 is a similar view taken from the opposite side, certain parts being removed. Fig. 3 is a ver-

45 tical cross section taken on the line 3—3 of Fig. 4. Fig. 4 is a cross section taken on the line 4—4 of Fig. 2. Fig. 5 is an elevation of a slightly different embodiment, certain parts being broken away. Fig. 6 is a similar view

50 of the actuating mechanism for the same. Fig. 7 is an enlarged longitudinal cross section of certain parts taken on the line 7—7 of Fig. 5. Fig. 8 is a cross section taken on the line 8—8 of Fig. 7. Fig. 9 is a detailed sec-

tional view showing the method of connecting certain levers in this embodiment.

Similar reference characters denote similar parts throughout the several views.

In order to render clearer the general nature of my invention, it may here be noted 60 that there is an imperative demand for a reliable speed change gear for use in several arts, notably that of motor vehicle construction.

The attempt to fill this demand by means of a frictional gear has been proved 65 useless owing to the lack of positive action of the same and wear upon the parts thereof, the latter necessitating the constant renewal and replacing of certain parts of the gear.

If it be attempted to use a positive speed 70 change gear of the conventional type there is constant danger of the stripping of the teeth, which results in the ruin of an expensive part, and there is also an undesirable jar and strain upon the mechanism upon the power 75

being applied or the speed varied. This shock is best reduced by having one gear constantly in engagement and thus there is no chance for a falling off in speed due to a total disconnection from the driving member in 80

the interval between the throwing out of one gear and the throwing in of another. It is also highly desirable that the gear thrown in 85

be entirely loose until it is fully in engagement with the co-acting gear, as in this manner the chances of injury to the teeth thereof are materially reduced. Another feature of prime importance in constructions of this 90

nature is the compactness of the gear, inasmuch as the space assigned thereto is often necessarily limited. The mechanism, moreover, must be simple and durable, as the wear and tear upon the parts inherent in the use of constructions of this type is often 95

severe.

The above and other advantages are attained in constructions of the nature of that hereinafter described.

Referring now to the drawings, there is shown at 1 in Fig. 2 a shaft which is here 100 shown as the driving member, although with certain slight changes in the parts it may be made the driven shaft if desired. Upon shaft 1 are keyed or otherwise fixed a series of gears 2, 3, 4, 5 and 6 which are of varying 105 diameters, as shown. Likewise mounted in the casing 7 in which is journaled shaft 1 is a shaft 8 having loosely mounted thereon plu-

rality of spur gears 9, 10, 11 and 12 each of which is adapted to intermesh with the adjacent gear upon shaft 1. Upon the gears mounted upon shaft 8 are outwardly projecting lugs or clutch members 13, each having one of their corners beveled, as shown at 14. These lugs are adapted to engage with rigid lugs 15 having beveled faces 16 projecting outwardly from the shaft, or preferably 10 from a sleeve 17 keyed thereon. The gears upon shaft 8 are adapted, upon being thrown to the left, with reference to Fig. 2 of the drawings, to mesh with the co-acting driving gear upon shaft 1, but as they are loose 15 thereon, they may be thrown into mesh without other shock than that occasioned by the slight inertia of the gear itself. Upon being fully intermeshed it will be noted that the projecting clutch members 13 will engage the 20 rigid clutch members 15 upon sleeve 17 and thus impart a rotary movement to shaft 8. If, however, this shaft is already driven at a rate of rotation higher than that of the gear which is thrown in, the shaft turns with reference to the latter and the beveled faces 14 and 16 co-acting one with another merely force the gear last thrown in slightly to the right and thus permit a free relative rotation 25 of the same with respect to the sleeve 17. It is therefore essential for this action that means be provided for the throwing of the gears into and out of engagement, and that such means be elastic so as to permit the slightest requisite lateral movement of the 30 gear in order to meet the contingency above pointed out.

Gear 6 is used for the purpose of a reversal of the direction of rotation of shaft 8 and, as will be noted from the drawings, is used only 35 when the parts are being driven at a low speed. This is for the largely obvious reason that upon the reversal of the direction of rotation of the driven part it is highly desirable that the same be as nearly stationary as possible in order to reduce the shock necessarily attendant thereon. The specific details of the reversing mechanism are not herein shown, and it is thought that it will be sufficient merely to indicate the action thereof.

40 Upon gear 12 being moved to the right, with reference to Fig. 2, it contacts and throws over a spring-pressed member 18 upon a lever 19 and thus there is a suitably proportioned idle gear thrown into mesh with the 45 gears 6 and 12, thus reversing the direction of rotation of the shaft 8. The specific details of this reversing mechanism are set forth in my co-pending case above referred to in which the same is claimed.

50 Journaled within case 7 are a series of rock shafts 20, 21, 22 and 23 each of which is provided with a pair of rigid arms 24 engaging the spur gear upon opposite sides of which they are positioned by means of flanged 55 members 25 pivotally connected to the ends

thereof. It will thus be seen that upon a swinging movement being imparted to these rock shafts the gear with which they are respectively connected will be reciprocated along the sleeve 17. These rock shafts are 60 selectively moved as follows:

Rock shaft 20 terminates in an arm 26 provided with a perforated lug 27, as shown in Fig. 3 of the drawing. Pivotaly mounted upon casing 7 is an arm 28 having upon the 65 end thereof a pin 29 adapted to enter a cam slot 30 in a cam disk 31. Arm 28 is connected to arm 26 by means of a rod 32 pivotally mounted upon the former and slidably and pivotally mounted by means of lug 27 upon arm 26. Springs 33 and 34 are interposed respectively between arms 26 and 28, and arm 26 and a knob 35 upon rod 32 for a purpose hereinafter explained. Cam disk 31 is positioned upon a shaft 36 and is provided 80 with a cam slot 37 upon its opposite face, controlling by means of a projecting pin 38 the movement of a pivotally mounted arm 39. Upon the outer end of rock shaft 21 is rigidly fixed an arm 40 which is connected with arm 39 by means of a rod 41 fixed upon one of the same and slidably with reference to the other thereof. A spiral spring 42 is positioned about this rod so as to permit a relative movement of lever arms 39 and 40 95 in one direction, but to prohibit the same in the opposite direction. It may here be noted that arm 26 corresponds to the driven gear 12 and hence two springs, 33 and 34, are used to cushion the movement in both directions, as this gear, owing to its relation to the reversing mechanism must have a certain freedom of movement with reference to the sleeve 17 in either direction.

Levers 43 and 44 are respectively mounted upon rock shafts 22 and 23 and are adapted to co-act with levers 45 and 46 engaging cam slots 47 and 48 upon the opposite faces of the cam disk 49 also fixed upon shaft 36. The latter levers are respectively provided with a connection with levers 43 and 44 which is substantially identical with that described between the lever arms 39 and 40. It will thus be seen that by means of properly formed cam slots any single one of the several levers 26, 40, 43 and 44 may be moved to a position corresponding to an engagement of the gear with which it is associated, and this movement is so cushioned by means of the spiral springs, as above pointed out, as to permit a lateral movement of the gear in question with reference to the cam lever which actuates the same. It will also be seen that the lever arm 26 may be rocked in either direction, thus permitting the same to 120 cause either a low speed forward drive or a reversal of the rotation of the driven part. The form of cam slots required and their relative position are roughly indicated in the drawings, slot 47, for example, in Fig. 1, be- 130

ing provided with a circular portion 50 adapted to maintain the lever 45 in a position corresponding to an inoperative condition of the gear 10 throughout a large portion of the rotation of cam 49. Upon the pin of lever 45 being brought within the portion 51 of the cam slot, however, the same is rocked to the right, with reference to Fig. 1, thus throwing the gear 10 into engagement with gear 3. In 10 a similar manner the several other gears may be thrown into engagement with their respective driving gears, it being noted that the cam slots are so positioned as not to throw out one gear before the succeeding 15 gear is fully in mesh, thus guaranteeing the continuity of the drive and largely reducing the shock upon changing the speed.

The twofold movement of lever arm 26 is brought about by means of the peculiar 20 form of the cam slot 30, whereby upon the cam being brought into such position as to bring pin 29 within the portion 52 the lever 28 is rocked toward the right, with reference to Fig. 3, and upon the pin being brought 25 within the extended portion 53 a movement thereof to the left results. The portion 54 which is circular with reference to the shaft 36 corresponds to a normal inoperative position of the gear 12.

30 The desired rotary movement of the cams 31 and 49 which, as above noted, are fixed upon shaft 36, is brought about by means of a spur pinion 55 driven by a segment 56 of an annular rack. This rack is fixed upon a lever 57 pivoted upon the casing of the gear and actuated in any desired manner, preferably by hand. A locking segment 58 is herein shown, the several notches 59 thereof co-acting with any desired form of ratchet or 35 locking mechanism 60 upon the lever, and each notch corresponding with a certain speed of transmission or with the position of the gears in which a reverse direction of drive is brought about. The cams 31 and 49 are 40 thus rotated by means of the swinging lever 57 so as to bring the desired gear upon shaft 8 into engagement with its co-acting driving gear and thus produce the desired speed of the driven part. It may here be noted that 45 the term "selectively" is used throughout the following claims to denote a mode of action by virtue of which any desired gear may be thrown into operative condition.

50 The method of use of the above described 55 embodiment of my invention is as follows: Assuming the parts to be in the normal condition shown in Fig. 2 and that it is desired to throw in the lowermost speed, namely, that corresponding to an operative condition 60 of gears 5 and 12, the lever 57 is swung so as to bring the portion 52 of cam slot 30 into engagement with the pin 29, thus resulting in such movement of lever arm 26 as to throw gear 12 into engagement with gear 5. It will 65 be noted that until these gears are fully in

engagement, the driven gear merely rotates upon the sleeve 17 but upon clutch member 13 engaging clutch member 16 a movement is transmitted to the shaft 8. If it be desired to increase the speed, lever 57 is simply 70 thrown to the next succeeding notch, whereupon cam 31 will be so rotated as first to move gear 11 and the clutch members upon this gear into engagement with their co-acting members upon the sleeve 17 and shaft 1, thus resulting in the driving of shaft 8 at an increased rate of speed and the slipping of clutch members 16 with reference to those formed upon the gear 12, due to the movement of this gear permitted by the 75 spiral spring 34. The complete movement, however, to the notch 59 corresponding to an active position of gear 11 will result in the throwing out of the gear 12 due to the engagement of the pin 29 with the portion 54 80 of its co-acting cam slot. In like manner the speed may be increased or diminished to any desired degree, the cam slots being so arranged as to cause the speed to be changed successively from one grade to that next 85 higher or lower, according as the speed is increased or diminished. If it is desired to reverse the direction of drive, it is necessary merely to throw lever 57 into such position 90 as to bring the portion 53 of cam slot 30 into engagement with pin 29, whereupon, as above indicated, the gear 12 is moved to the right, with reference to Fig. 2, and the reversing mechanism brought into operative condition. From this mode of operation it 95 will be noted that the number of gears, and, consequently, the number of different rates of speed possible in this device, may be indefinitely multiplied without changing the principle thereof.

10 It will thus be seen that I have provided a compact and efficient speed change gear whereby the rate of rotation of the driving part may be changed throughout any desired range substantially without shock or danger 110 of injury to the mechanism thereof. It will also be seen that there are no delicate parts to jam or otherwise become inoperative, and that the entire device is durable and easily kept in repair, and, in short, is well adapted 115 to stand the wear and tear of hard practical use. The entire change of speed and reverse of direction of drive, moreover, is controlled merely by the position of a single lever and thus the operation of the device is rendered 120 extremely simple. It will also be noted that there is absolutely no danger of locking the gears, with a consequent stripping of the teeth, as, owing to the cushioning means interposed between the cam actuated lever 125 arms and the gear shifting arms, it would be practicable to maintain all of the gears at once in mesh with the co-acting driving gears without injury to the parts.

130 Another marked advantage of this con-

struction is that owing to the form of the cam slots, none of the gears are thrown out until the succeeding gear is thrown in, thus absolutely avoiding any interval wherein the driving power is entirely disconnected. It will also be noted that the mechanism is inexpensive and easily repaired, the parts thereof being accessible merely upon the removal of a portion of the outer casing.

10 In Figs. 5 to 9 inclusive is shown a similar mechanism in which means for obtaining two speeds only are provided. In this embodiment the driven shaft 61 has mounted thereon a sleeve or series of sleeves 62 which are held in position by means of a key or feather 63. Clutch members 64 are formed upon this sleeve and are adapted to co-act with clutch members 65 formed upon the gears 66 and 67. The shifting of the gears is accomplished by means similar to that set forth with reference to the previously described embodiment, the same being actuated by means of cam slots 68 and 69 cut in a cam 70. Within these cam slots are pins 71 and 72 respectively positioned upon a lever 73 and a double-armed lever 74. These levers are loosely mounted upon the ends of the corresponding rock shafts 75 and 76, as shown, in the case of lever 73, in Fig. 9. Connected with lever 73 by means of a rod and spring similar to the connection above described, is a lever 77 fixed upon rock shaft 75 as by means of a set-screw 78. In a similar manner the lever arm 79 is connected with the double-armed lever 74, the movement thereof being cushioned in both directions by means of springs 80 and 81 so as to permit a cushioned movement thereof either to the left or right for the purpose of throwing in either the low speed forward drive or the reversing gear as outlined in connection with the first described embodiment. The method of operation of this embodiment is substantially identical with that first described and should be obvious from that description taken in connection with the drawings.

As many changes could be made in the above construction and many apparently widely different embodiments of my invention could be made without departing from the scope thereof, I intend that all matter contained in the above description or shown in the accompanying drawings shall be interpreted as illustrative and not in a limiting sense. I desire it also to be understood that the language used in the following claims is intended to cover all of the generic and specific features of the invention herein described and all statements of the scope of the invention, which, as a matter of language, might be said to fall therebetween.

Having now described my invention, what I claim as new and desire to secure by Letters Patent is:—

1. In a variable speed mechanism, in combination, a shaft, a plurality of gears of varying diameters fixed thereon, a second shaft, a plurality of gears slidably mounted thereon and adapted to mesh with said first mentioned gears, means adapted positively to throw said second mentioned gears into mesh with said first mentioned gears and to throw some of the gears out of mesh without breaking connection between all the gears, a lever controlling said means, and cushioning means interposed between said throwing means and said lever.

2. In a variable speed mechanism, in combination, a shaft, a plurality of gears of varying diameters fixed thereon, a shaft and plurality of gears slidably mounted thereon and adapted to mesh with said first mentioned gears, means adapted to throw one of said second mentioned gears into mesh with one of said first mentioned gears and to move some of the gears out of mesh without breaking connection between all the gears, a lever controlling said means, and cushioning means interposed between said throwing means and said lever.

3. In a variable speed mechanism, in combination, a shaft, a plurality of gears of varying diameters fixed thereon, a second shaft, a plurality of gears loosely and slidably mounted thereon and adapted to mesh with said first mentioned gears, means adapted positively to throw said second mentioned gears into mesh with said first mentioned gears, clutch mechanism upon said second mentioned shaft adapted to be engaged by co-acting clutch mechanism upon said second mentioned gears, a lever controlling the means whereby said second mentioned gears are thrown into engagement with said first mentioned gears and cushioning means interposed between said lever and said throwing means.

4. In a variable speed mechanism, in combination, a shaft, a plurality of gears of varying diameters fixed thereon, a second shaft, a plurality of gears loosely and slidably mounted thereon and adapted to mesh with said first mentioned gears, means adapted selectively to throw said second mentioned gears into mesh with said first mentioned gears and rigid clutch mechanism upon said second mentioned shaft adapted to be engaged by co-acting clutch mechanism upon said second mentioned gears.

5. In a variable speed mechanism, in combination, a shaft, a plurality of gears of varying diameters fixed thereon, a second shaft, a plurality of gears loosely and slidably mounted thereon and adapted to mesh with said first mentioned gears, means adapted positively to throw said second mentioned gears into mesh with said first mentioned gears and rigid clutch mechanism upon said second mentioned shaft adapted to be en-

gaged by co-acting clutch mechanism upon said second mentioned gears, a lever controlling the means whereby the said second mentioned gears are thrown into engagement 5 and cushioning means interposed between said throwing means and said lever.

6. In a variable speed mechanism, in combination, a shaft, a plurality of gears of varying diameters fixed thereon, a second shaft, 10 a plurality of gears loosely and slidably mounted thereon and adapted to mesh with said first mentioned gears, means adapted positively to throw said second mentioned gears into mesh with said first mentioned 15 gears, projecting lugs in fixed relation to said second mentioned shaft, a lug upon each of said second mentioned gears adapted to engage one of said first mentioned lugs upon the gear being thrown into operative position, a 20 lever adapted to actuate said throwing means and resilient means adapted to permit a lateral movement of said gear with said lever in fixed position.

7. In a variable speed mechanism, in combination, a shaft, a plurality of gears of varying diameters fixed thereon, a second shaft, a plurality of gears loosely and slidably mounted thereon and adapted to mesh with said first mentioned gears, means adapted 30 positively to throw said second mentioned gears into mesh with said first mentioned gears, projecting lugs in fixed relation to said second mentioned shaft, a lug upon each of said second mentioned gears adapted to engage 35 one of said first mentioned lugs upon the gear being thrown into operative position, a lever adapted to actuate said throwing means and resilient means adapted to permit a lateral movement of said gear with said lever in fixed 40 position, each of said lugs upon said gears being provided with an inclined face adapted to co-act with a similar inclined face upon the corresponding lug upon said shaft.

8. In a variable speed mechanism, in combination, a shaft, a plurality of gears of varying diameters fixed thereon, a second shaft, a plurality of gears loosely and slidably mounted thereon and adapted to mesh with said first mentioned gears, means adapted 50 positively to throw said second mentioned gears into mesh with said first mentioned gears, clutch mechanism upon said second mentioned shaft, co-acting clutch mechanism upon each of said second mentioned 55 gears adapted to engage said clutch mechanism upon said shaft upon the corresponding gear being thrown into operative position, an arm controlling said throwing means, an arm pivotally mounted adjacent said first 60 arm, a connection between said arms adapted to permit relative movement thereof in a certain direction and a spring adapted to cushion such movement.

9. In a variable speed mechanism, in com-

bination, a shaft and plurality of gears of varying diameters fixed thereon, a second shaft, 65 a plurality of gears loosely and slidably mounted thereon and adapted to mesh with said first mentioned gears, means adapted selectively to throw said second mentioned gears into mesh with said first mentioned 70 gears and to move some of the gears out of mesh without breaking connection between all the gears, said means comprising a lever arm corresponding to each gear, a second lever arm corresponding to each of said first mentioned lever arms, and resilient means interposed between each of said first mentioned arm and the corresponding second mentioned arm.

80 10. In a variable speed mechanism, in combination, a shaft, a plurality of gears of varying diameters fixed thereon, a second shaft, a plurality of gears loosely and slidably mounted thereon and adapted to mesh with 85 said first mentioned gears and means adapted selectively to throw said second mentioned gears into mesh with said first mentioned gears, said means comprising a lever arm corresponding to each gear, a second lever arm 90 corresponding to each of said first mentioned lever arms, resilient means interposed between each of said first mentioned arms and the corresponding second mentioned arm and a plurality of cams controlling the position of 95 said second mentioned lever arms.

11. In a variable speed mechanism, in combination, a shaft, a plurality of gears of varying diameters fixed thereon, a second shaft, a plurality of gears loosely and slidably mounted thereon and adapted to mesh with said first mentioned gears and means adapted 100 selectively to throw said second mentioned gears into mesh with said first mentioned gears, said means comprising a lever arm associated with each of said second mentioned gears, a lever arm corresponding to each of said first mentioned lever arms, resilient means interposed between each of 110 said first mentioned arms and the corresponding second mentioned arm and a plurality of co-axial cams controlling the position of said second mentioned lever arms.

12. In a variable speed mechanism, in combination, a shaft, a plurality of gears of varying diameters fixed thereon, a second shaft, a plurality of gears loosely and slidably mounted thereon and adapted to mesh with 115 said first mentioned gears and means adapted selectively to throw said second mentioned gears into mesh with said first mentioned gears, said means comprising a lever arm corresponding to each gear, a second lever arm corresponding to each of said first-mentioned lever arms, resilient means interposed between each of said first-mentioned arms and the corresponding second mentioned arm, a plurality of co-axial cams 120 125.

positively controlling the position of said second mentioned lever arms and a single lever controlling said cams.

13. In a variable speed mechanism, in combination, a shaft, a plurality of gears of varying diameters fixed thereon, a second shaft, a plurality of gears loosely and slidably mounted thereon and adapted to mesh with said first mentioned gears and means adapted selectively to throw said second mentioned gears into mesh with said first mentioned gears, said means comprising a lever arm corresponding to each gear, a second lever arm corresponding to each of said first mentioned arms, resilient means interposed between each of said first mentioned arms and the corresponding second mentioned arms, a plurality of co-axial disk cams positively controlling the position of said second mentioned lever arms, a spur gear upon the axis of said cams, a lever and a segment of an annular rack upon said lever intermeshing with said spur gear.

14. In a variable speed mechanism, in combination, a shaft, a plurality of gears of varying diameters fixed thereon, a second shaft, a plurality of gears loosely and slidably mounted thereon and adapted to mesh with said first mentioned gears and means adapted selectively to throw said second mentioned gears into mesh with said first mentioned gears, said means comprising a lever arm corresponding to each of said second mentioned gears, a second lever arm corresponding to each of said first mentioned arms, a rod pivotally connected with each of said second mentioned arms and slidably connected with each of said first mentioned arms, a spiral spring about each of said rods interposed between said arms, a plurality of cams controlling the position of said second mentioned arms and a lever controlling the positions of said cams.

15. In a variable speed mechanism, in combination, a shaft, a plurality of gears of varying diameters fixed thereon, a second shaft, a plurality of gears loosely and slidably mounted thereon and adapted to mesh with said first mentioned gears and means adapted selectively to throw said second mentioned gears into mesh with said first mentioned gears, said means comprising a lever arm corresponding to each gear and controlling the position thereof, a second lever arm corresponding to each of said first mentioned arms, a resilient connection between one of said first mentioned arms and the corresponding second mentioned arm adapted to cushion their relative movement in one direction, a resilient connection between one of said first mentioned arms and one of said second mentioned arms adapted to cushion their relative movement in both directions, means controlling the positions of said sec-

ond mentioned lever arms and a lever controlling said last mentioned means.

16. In a variable speed mechanism, in combination, a shaft, a plurality of gears of varying diameters fixed thereon, a second shaft, a plurality of gears loosely and slidably mounted thereon and adapted to mesh with said first mentioned gears, clutch mechanism upon said second mentioned shaft, co-acting clutch members upon each of said second mentioned gears adapted to engage the clutch mechanism upon said shaft upon the gear being thrown into operative position and means adapted selectively to throw said second mentioned gears into mesh with said first mentioned gears, said means comprising a lever arm corresponding to each gear, a second lever arm corresponding to each of said first mentioned lever arms, resilient means interposed between each of said first mentioned arms and the corresponding second mentioned arm and means controlling the positions of said second mentioned arms.

17. In a variable speed mechanism, in combination, a shaft, a plurality of gears of varying diameters fixed thereon, a second shaft, a plurality of gears loosely and slidably mounted thereon and adapted to mesh with said first mentioned gears, clutch members upon said second mentioned shaft, co-acting clutch members upon said second mentioned gears adapted to engage said clutch members upon said second mentioned shaft upon the gear being thrown into operative position and means adapted selectively to throw said second mentioned gears into mesh with said first mentioned gears, said means comprising a lever arm corresponding to each gear and controlling the position thereof, a second lever arm corresponding to each of said first mentioned arms, resilient means interposed between each of said first mentioned arms and the corresponding second mentioned arm, means adapted positively to control the positions of said second mentioned arms and a single lever controlling said last mentioned means.

18. In a variable speed mechanism, in combination, a shaft, a plurality of gears of varying diameters fixed thereon, a second shaft, a plurality of gears loosely and slidably mounted thereon and adapted to mesh with said first mentioned gears, clutch members upon said shaft, co-acting clutch members upon each of said second mentioned gears and adapted to engage said clutch members upon said shaft upon the gear being thrown into operative position, each pair of said clutch members being provided with inclined faces adapted to co-act one with another, and means adapted selectively to throw said second mentioned gears into mesh with said first mentioned gears, said means comprising a lever arm corresponding to each gear, a

second lever arm corresponding to each of said first mentioned lever arms and resilient means interposed between each of said first mentioned arms and the corresponding second mentioned arm.

19. In a variable speed mechanism, in combination, a shaft, a plurality of gears of varying diameters fixed thereon, a second shaft, a plurality of gears loosely and slidably mounted thereon and adapted to mesh with said first mentioned gears, clutch members upon said shaft, co-acting clutch members upon each of said second mentioned gears and adapted to engage said clutch members upon said shaft upon the gear being thrown into operative position, each pair of said clutch members being provided with inclined faces adapted to co-act one with another, and means adapted selectively to throw said second mentioned gears into mesh with said first mentioned gears, said means comprising a lever arm corresponding to each gear, a second lever arm corresponding to each of

said first mentioned lever arms, resilient means interposed between each of said first mentioned arms and the corresponding second mentioned arm, a plurality of cams controlling the positions of said second mentioned arms and a lever controlling the positions of said cams.

20. In a variable speed mechanism, in combination, a series of driving gears and a series of driven gears adapted to be moved into and out of engagement with each other, a series of arms for moving said driven gears, a cam disk for moving said arms, a controlling lever for rotating the disk, a locking dog on said lever, and an operating rod for said dog operated by direct downward pressures.

In testimony whereof I affix my signature, in the presence of two witnesses.

FRANZ MARKGRAF.
